UNITED STATES PATENT OFFICE

91,333

DESIGN FOR A SERVICE STATION

Guy L. Rosebrook, Cranberry Lake, N. J., assignor to Standard Oil Development Company, a corporation of Delaware

Application August 4, 1933. Serial No. 48,924

Term of patent 14 years

To all whom it may concern:

Be it known that I, Guy L. ROSEBROOK, a citizen of the United States, residing at Cranberry Lake, in the county of Sussex and State of New Jersey, have invented a new, original, and ornamental Design for a Service Station, of which the following is a specification, reference being had to the accompanying drawings, forming part thereof.

Fig. 1 is a front elevation of a service station, showing my new design;

Fig. 2 is a side elevation of the same to a somewhat reduced scale; and

Fig. 3 is a perspective view also to a somewhat reduced scale.

The rear of the service station is a blank wall.

I claim:

The ornamental design for a service station, substantially as shown and described.

GUY L. ROSEBROOK.
